UNITED STATES PATENT OFFICE.

JOSEPH LANE AND JOHN ROLSTON, OF MINNEAPOLIS, MINNESOTA; SAID ROLSTON
ASSIGNOR TO SAID LANE.

FLUSHING-VALVE FOR ELEVATED WATER-TANKS.

1,068,349.

Specification of Letters Patent.

Patented July 22, 1913.

Application filed April 18, 1912. Serial No. 691,762.

To all whom it may concern:

Be it known that we, JOSEPH LANE and JOHN ROLSTON, citizens of the United States, residing at Minneapolis, in the county of 5 Hennepin and State of Minnesota, have invented certain new, and useful Improvements in Flushing-Valves for Elevated Water-Tanks; and we do hereby declare the following to be a full, clear, and exact description of the invention, such as will enable others skilled in the art to which it 10 pertains to make and use the same.

Our invention has for its object to provide an improved flushing valve for elevated water towers and the like, and to such ends, generally stated, the invention consists of the novel devices and combinations of devices hereinafter described and defined in the claims.

20 In the use of elevated water tanks such as extensively employed in water works of towns and in many large manufacturing plants, it is customary to provide such tanks with depressed or hopper-like bottoms, and 25 to provide flushing valves in the bottoms of the tanks. These flushing valves have not, so far as we are aware, hitherto been satisfactory for several reasons, one of which may be mentioned, the tendency of 30 valves to be held open by sediment, and hence, to leak, and the tendency of the sediment to lock or hold the valves against free movements.

35 Our invention provides an extremely simple and highly efficient flushing valve for the above purpose, which is free from the above noted objections.

In the accompanying drawings which 40 illustrate the invention, like characters indicate like parts throughout the several views.

45 Referring to the drawings, Figure 1 is a view in side elevation with some parts broken away and some parts sectioned, showing an elevated water tower equipped with one of our improved flushing valves; Fig. 2 is a plan view of the flushing valve; and Fig. 3 is a section taken on the line $x^3 x^3$ on Fig. 2, and showing also a portion 50 of the hopper-like bottom of the tank.

The numeral 1 indicates the elevated tank formed with a depressed or hopper-like bottom 2 and supported by a suitable tower 3.

55 The numeral 4 indicates a water supply pipe which extends from the source of water

supply up into the tank through the bottom thereof, either at the axis of the tank or at one side thereof.

The numeral 5 indicates a flushing pipe which is screwed into or connected to a 60 valve seating plate or casing 6, bolted or otherwise rigidly secured to the lower portion of the hopper-like bottom 2 of the tank.

The numeral 7 indicates a vertically extended valve actuating rod which extends 65 parallel to the flushing pipe 5 and upward through a stuffing box 8 applied to said valve plate 6. The flushing pipe 7 extends to a suitable point of discharge and the valve actuating rod 7 is mounted in keeper 70 brackets 9 on the said flushing pipe, and is provided at its lower end, within easy reach from the ground, with an operating lever or hand piece 10.

The upper face of the valve seating plate 75 6 is machined off, preferably flat and smooth and is shown as horizontally disposed, although it may vary from the horizontal, but should be located at the bottom or lower portion of the tank, so that it may completely drain the tank and clear the same of sediment. 80

The numeral 11 indicates a valve proper, which is secured to the upper end of the rod 7, and the under face of which is machined 85 off, preferably smooth and flat, so that it will form a water tight joint with the smooth upper face of the valve plate 6. The rod 7 serves to impart oscillatory movements to the valve 11 and is shown as provided with a square shank 12 fitting the square seat in the said valve. A coiled spring 13 compressed between the hub of the valve 11 and the nut 14 on the threaded upper end of the rod 7, yieldingly presses 90

95 the hub end of the valve tightly against the face of the valve plate. The free end of the said valve 11 works under and is engaged by a laterally projecting segmental flange 15 of a segmental presser bar 16. This 100 presser bar 16 is mounted for slight vertical movements on studs 17, the lower ends of which are shown as screwed into the flange of the valve plate 6. As shown, there are three of these studs 17, and on each thereof, there is a coiled spring 18 compressed between the said bar 16 and nuts 19 applied to the threaded upper ends of the studs 17. The presser bar 16 does not engage with the face of the valve plate 6, and hence, the 110

springs 18 exert their force on the free end of the valve 11 and hold the same pressed tightly downward upon the face of the said valve plate. Obviously, by adjustments of the nuts 14 and 18, the tension under which the valve will be engaged with its seat may be varied.

In Figs. 2 and 3, the valve is shown in a normal or closed position by full lines, but in Fig. 2, the said valve is shown in an open position by dotted lines. As is evident, the valve is moved to and from an open position by a sliding or wiping action which keeps all sediment wiped clean from the face of the valve seat and from the face of the valve. This insures a tight joint and causes any wear which may take place to keep the valve and seat bound with a close liquid tight fit. Furthermore, accumulated sediment cannot interfere with the movements of its valve inasmuch as the edge thereof will readily force its way through any collected sediment. The valve may be quickly opened and quickly closed, and when closed forms a tight joint which will not leak. Also, the valve is of small cost and may be easily applied either to a new tank, or to a tank already erected.

What we claim is:

1. The combination with a tank, of a valve seat secured on the bottom thereof, a flushing pipe extended downward from a discharge port of said valve seat, a valve actuating rod extended upward through said valve seat, a valve connected to the upper end of said rod and mounted for oscillatory

sliding movements on the face of said valve seat, and a downwardly spring-pressed bar engaging and pressing downward on the said valve and holding the same tightly seated, the said valve being free for slight vertical movements on said rod, and a spring re-acting against the upper end of said rod and against said valve and assisting the spring-pressed bar to hold said valve tightly seated.

2. The combination with a tank, of a valve seat secured in the bottom thereof, a flushing pipe extending downward from a discharge port in said valve seat, a stuffing box applied to said valve seat, a valve actuating rod extended through said stuffing box and valve seat, a valve connected to the upper end of said rod for oscillatory movements therewith, but free for vertical movements thereon, a spring applied to the upper end of said rod and yieldingly pressing the hub of said valve downward on its seat, studs applied to said valve seat along the path of movement of the free end of said valve, a presser bar mounted for vertical movements on said studs and pressing the free end of said valve downward on its seat, and springs applied to said studs and yieldingly forcing said presser bar downward.

In testimony whereof we affix our signatures in presence of two witnesses.

JOSEPH LANE.
JOHN ROLSTON.
